UNITED STATES PATENT OFFICE

2,101,123

BLOWER

Christopher L. Wyche, York, Pa.

Application December 29, 1936, Serial No. 118,029

5 Claims. (Cl. 230—117)

This invention relates to blowers and more particularly to the type of blowers which are adapted to be used in connection with household furnaces to force a predetermined amount of air through the fuel so that the smaller inexpensive sizes of anthracite coal, such as rice, buckwheat, or screenings can be used for heating purposes, in lieu of the larger and more expensive sizes of coal.

An object of the invention is to provide an improved blower of the type in which a suitable constructed casing of simple form is adapted to be combined with a standard form of electric fan.

Another object of the invention is to provide an improved blower of the above type in which the casing of the blower is secured to the brackets of the electric fan which support the usual guard, the change over from electric fan to blower being readily made by detaching the guard, inserting the fan within the blower casing, and then securing the guard brackets to the blower casing.

Another object of the invention is to provide an improved blower of the above type in which means are included for altering the area of the inlet opening of the blower so that the desired quantity of air will be delivered by the blower to a furnace or other apparatus with which the blower is connected.

With the foregoing and other objects and advantages in view, the invention consists in the preferred construction and arrangement of the several parts which will be hereinafter fully described and claimed.

In the accompanying drawings:—

Figure 1 is a side elevation of a blower constructed according to the present invention, looking at the motor side thereof;

Fig. 2 is a vertical section of the blower casing taken on the line 2—2 of Fig. 1, the electric motor being shown in elevation;

Fig. 3 is a view similar to Fig. 1 of the blower casing and fan therein, the electric motor and one of the detachable disks for the inlet opening being omitted;

Fig. 4 is a side elevation of the detachable disk omitted from the structure shown in Fig. 3;

Fig. 5 is a detail section taken on the line 5—5 of Fig. 1; and

Fig. 6 is a detail section taken on the line 6—6 of Fig. 1.

Referring to the drawings, the device is supported by a pedestal 11 that has fixed thereto an electric motor 12.

The motor 12 has an armature shaft 13, to one extremity of which is fixed a fan 14 of well known type.

Fixed to the fan end of the electric motor 12 are four arms 15 which are adapted to support a suitable guard (not shown), when the device is used as an electric fan. The extremity of each arm 15 is bent laterally, as indicated at 16, Fig. 5, and near the end of each arm there is a hole 17 for the reception of a securing element, such as a screw or the like.

The parts above described constitute the elements commonly used in the construction of well known electric fans and need no further explanation. However, in order to utilize such fans with my invention the usual guard which surrounds the fan 14 is not needed and consequently such element is not shown, since it is removed 15 from the arms 15.

In order that the fan can be used as a blower for introducing a desired quantity of air under pressure to a furnace or other apparatus, I construct a suitable casing 21 which is adapted to be supported from the arms 15, so that the whole device is carried solely by the pedestal 11.

As shown, the casing 21 may be made of a single casting having a rather large annular opening 22 formed in the side wall 23 thereof 25 which faces the electric motor 12.

The purpose of forming the large opening 22 is to permit the insertion of the blades of the fan 14 into the casing without the necessity of disassembling the parts.

As shown in Figs. 2 and 3, it will be noted that the diameter of the opening 22 is slightly less than the diameter of the fan 14. However, the opening 22 is so formed in the side wall 23 with respect to the circumferential wall 24 of the casing 21 that the fan 14 can be readily inserted into the casing through the opening 22 by moving the fan laterally with respect to the opening 22 and shifting the casing 21 with respect to the several blades of the fan until such blades 40 are all disposed within the casing.

The wall 23 is formed with a plurality of lugs 25, one for each arm 15 (see Figs. 3 and 5).

A threaded hole 26 is formed in each lug 25, so that after the fan 14 has been inserted within the casing 21 the holes 17 can be registered with the holes 26, and screws 27 inserted therein for securing the casing to the motor 12.

The fan 14 is eccentrically disposed within the casing 21, and said casing is formed with an outlet or discharge end 28, to which may be connected a pipe, flexible hose, or the like (not shown), for conducting air under pressure from the blower to the apparatus with which the blower is adapted to be connected.

In order to provide means by which the desired amount of air will be drawn into the casing 21 by the fan 14, the ring 29 is detachably mounted on the inlet side wall 23 of the casing, 5 said ring being held in place by a plurality of screws 30.

The ring 29 is formed with an outwardly extending flange 31 which overlies the side wall 23, and an inwardly extending flange 32, the inner edge of which is rounded, as shown at 33. The flanges 31 and 32 are offset with respect to each other, as shown in Fig. 2, flange 32 alining substantially with the side wall 23 so that when the ring 29 is in position on the casing a smooth surface will be formed on the interior of the inlet side of the casing. 10

Between the flanges 31 and 32, the ring 29 is formed with two shoulders 34 and 35, shoulder 34 fitting singly against the edge of opening 22, and shoulder 35 being on the exterior of the ring. 15

For the purpose of providing an inlet in the casing of varying sizes, use is made of a pair of semi-circular plates or disks 36 and 37. 20

The disks 36 and 37 are similarly formed (see Fig. 4), and spring fingers or clips 40 are provided for detachably securing said disks in position on the ring 29 (see Fig. 6). 25

Each disk is shaped to conform around its periphery with the flanged portion 32 of the ring 30 29 so that when said disks are installed they form an inward extension of said ring, (see Fig. 2).

Along the adjoining edges of the disks 36, 37 the central portions are cut out, as indicated at 38, 39, 35 so that a suitable annular opening is provided around the projecting portion of the casing of the electric motor 12 which supports the portion of the shaft 13 between the main body of the motor and the fan 14, the cut-out portions 38, 39 provide a restricted inlet opening for the air which 40 is drawn into the casing 21 by the fan 14.

As shown in Figs. 1 and 2, when a small quantity of air is wanted, the two disks 36 and 37 are mounted on the ring 29. 50

When a greater quantity of air is required, one or both of the disks can be removed. In Fig. 3, the disk 36 is not shown, and consequently the area of the inlet opening is approximately the area of one half of the internal diameter of the ring 29, plus the area of the cut out portion 39 45 of the disk 37, and minus the inner projecting portion of the motor structure heretofore referred to.

The outer side wall 41 of the casing 21 converges inwardly towards the center, as indicated at 42 Fig. 2, so as to conform somewhat to the general outline of the outer edges of the fan blades. By 45 this construction the general contour of the interior of the casing is such that when the fan draws air into the casing through the inlet opening the air will be forced outwardly towards the circumferential wall 24 of the casing. At the same time the air is forced in the direction of rotation of the fan, as shown by the arrow Fig. 1, 50 towards the outlet 28.

The contour of the casing 21 is such that as the air approaches the outlet 28 the space within casing increases in area and thus accommodates an increasing volume of air. Thus the air continues to travel in the same direction of the fan blades until it reaches the outlet at the discharge end 28. Since the discharge end 28 is tangential to the casing, the air flows away from the fan blades and the blades of the fan continue to travel in a circular direction. 5

Having thus described my invention, what I claim is:

1. An apparatus of the class described, comprising a rotatable fan, an electric motor for operating said fan, a spiral casing enclosing said fan and having an inlet opening adjacent one end of the motor and an outlet opening, a plurality of arms carried by the motor and projecting outwardly therefrom, means for detachably connecting the extremities of said arms with said casing whereby the casing is supported solely by said motor, a ring detachably mounted in said inlet opening of the casing, and a plurality of disks detachably carried by said ring for varying the area of said inlet opening. 10

2. An apparatus of the class described, comprising a rotatable fan, an electric motor for operating said fan, a casing supported from said motor and enclosing said fan, an inlet opening formed in the side wall of said casing facing the motor, a ring detachably mounted in said inlet opening, and a plurality of disks detachably carried by said ring for varying the area of said inlet opening. 25

3. An apparatus of the class described, comprising a rotatable fan, an electric motor for operating said fan, a casing supported from said motor and enclosing said fan, an inlet opening formed in the side wall of said casing facing the motor, a ring detachably mounted in said inlet 40 opening, two semicircular disks, and means for detachably mounting said disks in said ring. 35

4. An apparatus of the class described, comprising a rotatable fan, an electric motor for operating said fan, a casing supported by said motor and enclosing said fan, an inlet opening formed in the side wall of said casing adjacent said motor, and a plurality of detachable elements mounted on the inlet side of said casing for varying the size of the inlet opening. 50

5. An apparatus of the class described, comprising a rotatable fan, an electric motor for operating said fan, a casing enclosing said fan, an inlet opening formed in the side wall of said casing adjacent said motor, a flanged ring detachably mounted in said inlet opening and having an inner wall flush with the inner portion of the side wall of the casing, flanged disk mounted on said ring for controlling the area of said inlet opening, and means for detachably connecting said disk with said casing. 60
